UNITED STATES PATENT OFFICE.

LABAN ELLSWORTH JONES AND CHARLES ROSWOLD WRAITH, OF ANACONDA,
MONTANA.

AUTOMATIC COMBUSTION REGULATOR.

Application filed April 5, 1920. Serial No. 371,540.

To all whom it may concern:

Be it known that we, LABAN ELLSWORTH JONES and CHARLES ROSWOLD WRAITH, citizens of the United States, residing at Anaconda, in the county of Deerlodge and State of Montana, have invented certain new and useful Improvements in Automatic Combustion Regulators, of which the following is a specification.

10 This invention relates to apparatus for the automatic regulation of combustion in combustion chambers.

The main object of this invention, generally stated, is to provide an apparatus 15 which will at all times and under all influencing conditions automatically control the feed of fuel, such as pulverized coal, oil, or gas, the supply of oxygen (air), the draft, or all as stated, in the combustion chambers 20 of metallurgical and industrial furnaces, ovens, and boilers, so as to accomplish and maintain a balanced combustion, complete or partial as desired.

A further object of this invention is to 25 provide an apparatus whose novel arrangement, construction and combination of parts furnish automatic means for the operation control, or regulation of other mechanical devices to which the motion transmitted by 30 this apparatus is applicable and to which the impulse governing the operations of this apparatus is an influencing factor.

For the purpose of discussing the main object of this invention, namely the automatic regulation and control of combustion 35 in combustion chambers, we will consider its application to reverberatory smelting furnaces to which application the apparatus has been developed to its present stage.

40 It is a well determined fact that combustion in such a furnace is disturbed by the slightest variations in draft pressure, which variations result from changes in atmospheric conditions, opening and closing of 45 doors and ports to the furnace, dropping charges, and numerous other causes and conditions. The combustion mixture is changed to an extent where an excess of air or an excess of incompletely burned products of 50 combustion are prevalent. This unbalanced condition results in a waste of heat, poor fuel efficiency, spasmodic increase and decrease of temperature with the resultant working of the chamber roof and settings by

expansion and contraction and generally an 55 inefficient operating condition. Further than this an incomplete combustion contributes to a poor heat distribution which decreases smelting efficiency as a consequence. 60

This invention when installed in connection with a metallurgical furnace, burning pulverized coal, oil, or gas, operates to automatically increase or decrease the fuel, the oxygen, or both as required for a proper 65 combustion mixture according to the slightest variation of draft pressure.

The fuel is blown into the furnace through burner pipes by air under compression. This air supply, commonly referred to as 70 "primary" air usually amounts to, in the case of pulverized fuel, less than 50% of the total air required for a complete combustion of the fuel supplied. The balance of the air necessary for a proper combustion mixture 75 is drawn into the furnace by the injector effect of the primary air flowing through the burner pipe and the draft of the furnace.

The fuel feeding mechanism, in the case 80 of pulverized coal and the valves in the case of oil or gas are usually adjusted for a fixed rate of fuel feeding. The air, primary and secondary, for the combustion of the fuel is likewise a fixed amount, dependent on the port openings. The draft, the other or third 85 factor in the combustion, is a variable throughout a considerable range, because of causes previously mentioned. It can be readily seen that, for instance where there is an increase in draft pressure, the fuel and 90 air supply being fixed, an excess of secondary air is drawn into the furnace by reason of this increase of draft pressure. This excess of air requiring heat units to 95 bring its temperature up to the temperature of the escaping gases robs the furnace of just this amount of heat. Also by reason of this increase in draft pressure the velocity of the gases leaving the furnace is greater with the result that the furnace is robbed of heat 100 units it can ill afford to lose.

The reverse of this condition is a decrease 105 of draft pressure which acts to cause a decrease in the amount of secondary air drawn through the air ports into the furnace thus resulting in an insufficient quantity of oxygen entering the combustion chamber to completely consume the fuel supplied. This in-

complete combustion of the fuel results in a gas carrying free carbon monoxide, which passes out of the furnace into the flue system where it obtains oxygen from the air leaking through the settings and from open doors, and burns with the generation of a high heat where it is least desired.

When such conditions as these are noted by the furnaceman he attempts to regulate 10 by operating the adjustment of the fuel feeding mechanism by hand to give more or less fuel as required or he opens or closes the air ports to give more or less air as required.

The accuracy of such regulation is based 15 solely on the ability of the furnaceman to judge conditions from observation. The disadvantages of this method of regulation are many.

It is obvious that some automatic means 20 of constant regulation and control is highly desirable and would result in, not only a saving of fuel but also in a smooth steady operating condition and numerous other benefits which only a man familiar with the 25 operations of metallurgical furnaces can fully appreciate; hence the development of an automatic combustion regulator as is herein described.

For a full understanding of the invention 30 reference is had to the accompanying drawings in which

Fig. 1 is a plan view;

Fig. 2 a front view of a device representing 35 one embodiment of the invention;

Fig. 3 another embodiment thereof; and Fig. 4 is a detail view on a larger scale of part of the mechanism disclosed in Figs. 1 and 2.

The operating mechanism constituting the 40 form of the invention shown in Figs. 1 and 2 is contained in a casing 1. A draft pressure indicating and recording means of the type forming the subject matter of my application Serial No. 367,458 filed March 20, 45 1920 comprises a pan receptacle 3 which contains a light liquid, preferably oil, for sealing purposes and through the center of which protrudes a draft pipe 4 to a sufficient height to clear the surface of the liquid. A 50 pan 5 of smaller diameter than the receptacle hangs bottom side up in the sealing liquid thus forming a closed chamber sealed by the liquid, the only communication to this chamber being the draft pipe 4.

55 The inverted pan 5 is suspended from a chain 6 connecting it to a system of levers 7 and 8 and is counterbalanced by weights around a knife-edge center. Weight 9 acts as a counterbalance for the parts operating 60 around the knife-edge center while weight 10 acts to counterbalance any force exerted upon pan 5 or in other words acts to counterbalance or weigh the draft pressure. To the lever system is attached arm 11 carrying a 65 pen for the purpose of indicating and re-

cording the draft pressure on the calibrated chart 12 revolved by means of a constant speed motor such as a clock mechanism 13.

In order to make the device thus far described available for automatically controlling the fuel feed mechanism we provide the following means:

The lever or arm 8 preferably includes two spring arms 14 and 15 carrying contact points 14'' and 15'', respectively, mounted 75 on iron armatures 14' and 15'.

About the axis of the lever 8 is revolubly mounted another arm 16 carrying at its lower end upon an insulating bar 16' two small magnets 17 and 18 provided with contact points 17' and 18'. As is shown more clearly in detail in Fig. 4, these contact points 17' and 18' are positioned to move in the same plane of angular motion as the contact points 14'' and 15'' respectively and to 85 make contact therewith. Screws 19 and 20 may extend through the magnets to define the contact points 17' and 18' and afford adjustment thereof in the well known manner.

The magnet 17 is energized by a winding 17'' and the magnet 18 by a winding 18'' when contact is established between contacts 17' and 14'' or 18' and 15'', respectively, for a purpose to be subsequently referred to.

One pole of the battery is connected to the spring arms 14, 15 through connection 7' and levers 7 and 8, while the other pole of the battery is connected through conductor 43 to one terminal of the solenoids 21 and 22. The other terminals of solenoids 21 and 22 are connected through conductors 44 and 45 to the windings 17'' and 18'' respectively. The free end of the winding 17'' is connected to contact point 17' and the free end of the winding 18'' to the contact point 18'. Motor 23 which preferably is a three-phase alternating current motor is geared up with a shaft 24 which controls through sprocket 24' the fuel feeding mechanism (not shown). Through stationary contact posts 25, 26, 27, 28, movable contact posts 29, 30 and 31, 32 carried by the plungers 21' and 22' respectively, and connections 33, 34, 35, 36 and 37 the motor is caused to run in one direction when the plunger 21' is operated and in opposite direction when plunger 22' is operated.

Upon shaft 24, which is so geared with the motor 23 as to obtain a large reduction in speed, travels a nut 38 one way or the other according to whether the fuel feed is increased or decreased. This nut is pivotally connected to the arm 16 by a rod or link 38.

The operation of the device is as follows: Assuming that the draft pressure increases or decreases from normal indicated on the chart 12 by the zero line, the arm 8 will swing in one case to the left, in the other to

the right or vice versa and will eventually cause contact between the contact points 14" and 17" or 15" and 18". Just as soon as contact is made current will flow from the battery through winding 17" and solenoid 21 or through winding 18" and solenoid 22, as the case may be, causing the motor to be run in one direction or the other.

Once a magnet 17 or 18 is energized, it tends to take the corresponding armature 14" or 15" along when the arm 16 is moved by the nut 38 through the link 38'. The spring arms 14 and 15 are so constructed as to angularly yield a definite amount before they break contact with the magnets. By properly designing the resistance of the arms 14 and 15 against bending, the windings 17" and 18" or both and by adjusting the screws 19 and 20, the feed control may be made accurately responsive and sensitive. The time required for the magnet to move from its position of making contact to its position of breaking contact is the time necessary for the operation of the feed control means and this time may be accurately determined by the means disclosed.

After the contact between one of the arms 14 or 15 and the corresponding magnet 17 or 18 is broken, the motor stops. As soon as the draft pressure changes and the other of the spring arms contacts with the other magnet, the other solenoid will be energized and the motor will be operated in reverse direction.

In Fig. 3 is represented a device which, while based on the same general principles, is used to regulate to maintain a substantially constant draft pressure. It is obviously possible to maintain a substantially constant supply of fuel or combustion mixture and by keeping the draft pressure substantially constant a balanced steady combustion is obtained.

The arrangement represented in Fig. 3 is generally the same as that shown in Figs. 1 and 2, with the difference, however, that the motor 23' and the shaft 24' driven thereby are located a distance from the other mechanism. The shaft 24' is connected to a damper 30 controlling the flue 31 or other conduit through which the air passes to the combustion chamber. It is understood that the motor may be connected to any other draft-controlling device, the particular arrangement being referred to only for purposes of illustration.

The contact elements 17" and 18" and the elements 17, 18, 17", 18", 19 and 20 are mounted on a stationary support 32, the arm 16 and the link 38' being omitted.

When the draft pressure changes from normal, the needles 14, 15 will move to the right or left exactly as previously described and will cause the operation of the motor in the proper direction to adjust the draft back

to normal. By properly correlating the spring arms 14, 15 the magnet windings 17", 18", the ratio of the reduction gearing, etc., the draft control may be made sensitive and accurately responsive. Various refinements obvious to persons skilled in the art, may of course be introduced to make the draft adjustment smooth i. e. to prevent overshooting and corresponding fluctuations of the draft pressure. The arrangement shown and described, however has been found to give complete satisfaction.

It is obvious that the draft regulator may be easily applied also to installations in which artificial draft is used. In such cases the motor will be used simply to adjust the speed of the blower motor or other pressure device in the well known way.

It should be understood that the specific arrangement constitutes only one embodiment of the invention, although this form is at present considered as a preferred form. The important feature in its broader aspect is time controlled means operative upon contact between the arm 8, or other pressure-responsive element, and either one of the contacts 14", 15", to maintain contact for an appreciable length of time. The arrangement essentially includes two important features:

- (1) Means operative upon contact to positively maintain contact;
- (2) Means operative upon contact to make the holding action ineffective after a definite time interval.

While we prefer the use of spring blades as part of arm 8 and a movable element such as nut 38 acting upon the support of the magnets to move them relatively to arm 8, the time interval may be introduced in various other ways and it is emphasized that we do not intend to limit ourselves to the particular form of embodiment disclosed.

While we have described two embodiments of the invention, one in which the feed of the combustion mixture is regulated and one in which the draft pressure is regulated, it is of course possible to regulate both either independently or independently and such arrangement we contemplate as within the scope of invention. In fact the movement of the pressure gage may be translated to regulate independently or independently any factor entering into the process of combustion.

In the foregoing the various elements have been referred to without accounting for their specific structural relation and support. It is obvious that there is considerable latitude in the arrangement. In the drawings is shown a frame composed of upright frame members 40 and transverse members 41 and 42 for pivotally supporting the lever system 7, 8, arm 16, shaft 24 and other parts.

The connections from the motor 23 to the

source of power and to the switch mechanisms are not described in detail since they are a matter of common knowledge and well understood by persons skilled in the art.

5 We claim:

1. In apparatus of the character described, the combination with a pressure responsive means including a pivotally mounted element and means for translating variations 10 of pressure into angular movement of said element and means for regulating conditions in a combustion chamber including an electric motor and electric circuits for controlling the motor, of an arm connected to the 15 said element and partaking of said angular movement, contact elements disposed on opposite sides of the arm in the plane of movement thereof, said arm being adapted to contact with said contact elements, means operative 20 upon contact between the arm and either of said contact elements to apply a force sufficient to hold the arm to the contact element against a predetermined force tending to break contact, said circuits being controlled 25 by the said arm and the said contact elements and time-controlled means operative to make said holding force ineffective.

2. Apparatus according to claim 1 in which the force is applied by a magnet associated 30 with each contact element and the arm carries armatures co-operating with the magnets.

3. Apparatus according to claim 2 in which the magnets are electro-magnets energized 35 by windings connected to said circuits.

4. Apparatus according to claim 1 in which the arm forms a part of said circuits.

5. Apparatus according to claim 1 in 40 which the arm includes resilient means permitting a limited angular movement of the arm during contact between the arm and either of the contact elements.

6. Apparatus according to claim 5 in 45 which the resilient means comprises spring blades on the arm, each blade carrying an armature.

7. Apparatus according to claim 1 in 50 which the circuits include electromagnetic means, the motor and the said electro-magnetic means being so related that when one of the circuits is energized the electro-magnetic means therein will cause the motor to run in one direction and when another circuit is energized the electro-magnetic means therein will cause the motor to run in opposite direction.

8. Apparatus according to claim 1 in 55 which the contact elements are made adjustable toward and away from each other.

9. In apparatus of the character described, the combination with a member having movement responsive to variations of the pressure of a pressure medium, of contact elements on opposite sides of said mem-

ber and in the plane of movement thereof, said contact elements adapted to contact with said member, means operative upon contact between the said member and either of said contact elements to apply a force 70 tending to hold them in contact, resilient means for permitting a limited movement of said member while the latter and either of the contact elements are in contact and means operative upon contact between the 75 said member and either one of said elements to move the latter to cause a breaking of contact.

10. In apparatus of the character set forth, the combination with a draft gauge 80 having a movable element, a spring blade element connected to said movable element, contact elements located on opposite sides of the spring blade element and supported for movement in the direction of the movement thereof, a source of electricity, a connection between one pole of said source and the spring blade, a connection between the other pole and each of said contact elements, electromagnetic means in series with each contact element, means tending to hold the spring blade mechanism in contact with either of the said contact elements, a motor, circuits therefor including a switching mechanism connected with each of the electromagnetic means for operating the motor in opposite directions and means responsive to the action of the motor for moving the contact elements relatively to the spring blade mechanism and out of contact therewith. 90

11. Apparatus according to claim 10 in which the means responsive to the action of the motor comprises a nut traveling upon a screwthreaded shaft driven by the motor and connected to the contact elements. 105

12. The combination with a combustion chamber and a draft gauge connected therewith, of means for altering the conditions in the combustion chamber and mechanism responsive to the action of the draft gauge for actuating said means, said mechanism including a motor, a shaft interconnecting the motor and the said means, electric circuits for operating the motor in opposite directions, switch mechanisms in said circuits, separate means for operating said switch mechanisms, said switch operating means comprising an electro-magnetic means connected to each switch mechanism, a source of electricity, a circuit including the source and one of said electromagnetic means, a circuit including the source and the other of said electromagnetic means, means carried by the draft gauge for opening and closing either of said circuits and means operative incident upon the closing of one of said circuits to maintain it in closed condition for a sufficient period of time to actuate said means for altering the conditions in the combustion chamber. 110 115 120 125 130

13. In apparatus of the character described the combination with pressure responsive means including a movably mounted member and means for translating variations of pressure into movement of said member, electrical contact elements on opposite sides of the movable member in the path of motion thereof, means for regulating conditions in a combustion chamber including
- 5 15
10 an electric motor and electric circuits for controlling the motor, one of said circuits including said movable member and one of said contact elements and another of the said circuits including the movable member and the other contact element, means operative upon contact between the movable member and either of said contact elements for holding the movable member and the contact element in contact with each other and time controlled means operative upon contact between the said movable member and either one of said contact elements to make the holding action ineffective.
